(57) **CLAIM**

The ornamental design for a curtain light, as shown and described.

DESCRIPTION

FIG. 1 is a front, right, top perspective view of a curtain light, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view thereof in a detached state;

FIG. 10 is a front, right, top perspective view of its reduced scale, indicating the usage environment; and,

FIG. 11 is an enlarged view of detail 11 in FIG. 10.

The dashed broken lines in the figures are for the purposes of illustrating portions of the curtain light and form no part of the claimed design.

The dash-dot-dash broken lines are for notating enlarged views and form no part of the claimed design.

The broken lines in the FIG. 10 and FIG. 11 are for environmental purposes only and form no part of the claimed design.

1 Claim, 11 Drawing Sheets
